UNITED STATES PATENT OFFICE.

SAMUEL J. BURNS, OF VINITA, OKLAHOMA.

VALVE-TESTING DEVICE.

Application filed July 25, 1922. Serial No. 577,417.

To all whom it may concern:

Be it known that I, SAMUEL J. BURNS, a citizen of the United States, residing at Vinita, in the county of Craig and State 5 of Oklahoma, have invented certain new and useful Improvements in a Valve-Testing Device, of which the following is a specification.

The present invention relates to a valve 10 testing device and has for its principal object to provide means for testing tire valves to ascertain whether or not the same are leaking.

Another important object of the invention 15 is to provide a device of this nature which will be simple and efficient in construction light in weight, compact, durable, inexpensive to manufacture, and well adapted to the purpose for which it is 20 designed.

With the above and numerous other objects in view the invention resides in certain novel features of construction as will be hereinafter more fully described and 25 claimed.

In the drawing:—

Figure 1 is a perspective showing the 30 valve tester in conjunction with a tire valve, and

Figure 2 is a longitudinal section therethrough.

Referring to the drawing in detail it will be seen that a tube 1 is provided with an aperture closure 2 at one end while the 35 other end thereof is open. A piston 3 is movable inside the tube 1 and is provided with a rod 4 that projects through the aperture in the closure 2. A pierced block 5 formed preferably of rubber is situated in 40 the tube adjacent the closure 2 for frictionally engaging the rod 4 so as to offer some resistance to its movement. Adjacent the open end of the tube 1 there is situated a block 6 of yieldable material such as rubber pierced as at 7. The blocks 5 and 6 45 are forced into the tube 1 and in so doing they are compressed so as to frictionally engage the inner surface of the tube and thus will be prevented from accidental displacement.

At 8 I have shown a portion of an ordinary tire valve being provided with the stem 9. The tester is placed thereon as is indicated in Figure 2, the piston 3 having 55 been pushed adjacent the open end of the tube and the yieldable block 6 resting upon

the mouth of the valve 8. It will be seen that if there is any leakage through the valve it will cause the piston 3 to rise in the tube, likewise causing the rod 4 to rise. 60 By having the yieldable block 6 the tester may be pressed tightly upon the mouth of the valve and prevent any leakage at the connection between the tester and the valve. The friction producing member 5 for the 65 rod 4 prevents the same from raising suddenly and causes the same to move up gradually so that the amount of the leakage may be more readily ascertained by the user of the testing device. 70

It is thought that the construction and operation of the device will be readily understood without a more detailed description thereof. It is, however, desired to point out that the present embodiment 75 of the invention has merely been disclosed by way of example and that numerous changes in the details of construction and in the combination and arrangement of parts may be resorted to without departing 80 from the spirit of the invention as hereinafter claimed.

Having thus described my invention what I claim is:—

1. In combination, a tube having a pierced 85 closure at one end and open at the other end, a yieldable pierced block at the open end of the tube adapted to be engaged with a tire valve, a piston in the tube, a rod extending from the piston through the 90 pierced closure of the tube and friction means situated adjacent the pierced closure for engaging the rod to normally hold it stationary in an adjusted position.

2. A device of the class described includ- 95 ing a tube, a pierced block at one end of the tube formed of yieldable material and adapted to be engaged by a tire valve and a pierced block at the other end formed of frictional material, a piston in the tube, and 100 a rod attached to the piston and penetrating the pierced block of frictional material so that said block last mentioned frictionally engages the rod to hold it normally in a stationary position. 105

In testimony whereof I affix my signature in presence of two witnesses.

SAMUEL J. BURNS.
